UNITED STATES PATENT OFFICE.

GEORGE W. BOLL, OF MOUNT HOPE, KANSAS.

STORAGE-BIN.

932,243.

Specification of Letters Patent. Patented Aug. 24, 1909.

Application filed April 13, 1908. Serial No. 426,856.

To all whom it may concern:

Be it known that I, GEORGE W. BOLL, a citizen of the United States, residing at Mount Hope, in the county of Sedgwick and 5 State of Kansas, have invented certain new and useful Improvements in Storage-Bins; and I do hereby declare the following to be a full, clear, and exact description of the invention, such as will enable others skilled in 10 the art to which it appertains to make and use the same.

My invention relates to improvements in storage receptacles or bins adapted for holding grain etc., and has to do particularly 15 with the construction of the roofs of such bins.

It has for its object to provide a roof for a granary or storage bin of the knock-down type which is simple in construction and 20 very strong and durable.

Further objects of the invention will appear from the following description.

The invention consists in the features of construction and combinations of parts here- 25 inafter described and specified in the claims.

In the accompanying drawings, illustrating the preferred embodiment of my invention: Figure 1 is a broken elevation of a bin constructed in accordance with my invention, partly in central section. Fig. 2 is a 30 top plan view. Fig. 3 is an under plan view of the roof. Fig. 4 is a broken sectional view on the line y—y of Fig. 2. Fig. 5 is a detail view of one of the roof beams. Fig. 6 is a 35 broken plan view of the hatchway in the roof. Fig. 7 is an under plan view of the hatch, and Fig. 8 is a broken detailed view showing a modified construction of tubular support at the center of the roof.

Referring more particularly to the drawings, 40 1 designates the body of the bin, the wall of which is preferably of circular or cylindrical form and is composed of a number of superposed circular sections, the num- 45 ber and diameter of said sections being gov- erned by the desired capacity of the completed bin.

As the specific construction of the body of the bin forms the subject matter 50 of my co-pending application Serial No. 409,554, filed January 6, 1908, I do not deem it necessary to describe it herein in detail.

The roof 2 is supported upon a plurality 55 of radially arranged roof beams or rafters 3 having horizontal base flanges 4 and vertical flanges 5. Each of said roof beams is also provided with depending lugs 6 and 7

respectively at its opposite ends. These lugs are formed by cutting and bending down the extremities of the horizontal flange 4. The inner lug 6 is bolted or otherwise secured as 60 at 8 to a tubular support 9 arranged at the center or apex of the roof. The outer lug 7 is secured at 10 to an angle iron band 11 which is in turn fastened to the upper edge 65 of the body or walls of the bin. The outer end of the vertical flange 5 extends over and rests upon said angle iron 11 which serves to strengthen the top of the bin against the pressure of the grain from the inside. It will be noted that the lugs 6 and 7 are re- 70 spectively arranged at acute and obtuse angles to the horizontal flanges in order to give the proper pitch to the roof when in position.

The roof proper comprises plates 12 preferably made of sheet metal, every alternate plate having vertical flanges 13 at its lateral edges and the others being provided with inverted U-shaped flanges 14 at their lateral edges. The sections having the vertical flanges are placed between the beams 3, with 80 one edge of each plate resting on the horizontal or base flange of one of said beams and said vertical flanges registering with the vertical flanges 5 of the beams. The plates carrying the inverted U-shaped flanges are 85 then positioned with said flanges extending over the vertical flanges of the roof beams and other plates thereby forming water tight joints. The plates and beams are fastened together by means of bolts 15 90 passed therethrough. The inner ends of the roof plates are cut to conform to the outer surface of the tubular support 9. A conical cap piece 16 to shield the opening of said tubular support is arranged on the apex of 95 the roof and is supported by arms 17 carrying clips 18 engaging opposite flanges of the roof plates and fastened thereto by means of bolts 19.

In one of the roof plates there is formed 100 a filling hatchway 20 which is preferably pointed at its upper end. Around the sides and ends of said hatchway are fastened angle irons 21 having lateral flanges 22. The upper part of the lateral flanges on the 105 sides of the hatchway are cut away at 23. When it is desired to remove the hatch 24 which has flanges 25 corresponding to and adapted to engage the flanges around the hatchway, it is only necessary to move said 110 hatch upwardly until the flanges 25 clear the flanges 22 on the sides of the opening

after which the hatch can be raised. It will be observed that the upper pointed ends of the hatch and hatchway are protected from rain by the overhanging cap piece 16. The 5 bin may be filled by means of the hatchway or a whole roof plate may be easily removed after taking out the bolts which secure it to the roof beams.

A perforated ventilating pipe 26 is centrally arranged in the bin with its upper 10 end extending into the tubular support 9 in the roof. Said ventilating pipe is secured to the bottom of the bin in any suitable manner and is incased in a fine mesh wire screen 15 27. to prevent the grain from entering the pipe 26 by means of the perforations therein. A horizontal pipe section 28 communicates with the ventilating pipe through the bottom of the bin and also with the outside air. 20 This insures perfect circulation of air through the bin and prevents the grain stored therein from molding.

In Fig. 8, I have illustrated a modified construction of tubular support 29 at the 25 center of the roof. Said tubular support is provided with a flange 30 around its lower edge to support the inner ends of the beams 31 which do not have any depending lugs at 30 said ends but are secured to said flange by bolts 32. The upper face of said flange is preferably beveled to conform to the incline of the beam which, of course, gives the pitch to the roof.

I claim:

35 1. The combination, with a wall, of a roof beam having a horizontal flange and a vertical flange, one extremity of said horizontal flange being cut and bent to form a lug secured to the upper edge of said wall, the 40 corresponding end of said vertical flange extending over and resting upon the wall, and roof plates supported on said beam.

2. The combination, with a wall, of a roof

beam having a horizontal flange and a vertical flange, one extremity of said horizontal 45 flange being cut and bent to form a lug secured to the upper edge of said wall, the corresponding end of said vertical flange extending over and resting upon said wall, a roof plate supported at one edge on the horizontal flange of said beam and provided with an upstanding flange registering with the vertical flange on said beam, and another roof plate having an inverted U-shaped flange at its edge which extends over the 50 vertical flange on the beam and the upstanding flange on the other plate.

3. The combination, with a roof having a hatchway therein bounded on all but one side by bent projecting flanges, and a hatch 60 having turned flanges on all but one side adapted to engage said first mentioned flanges, portions of the flanges at opposite sides of the hatchway being cut away to allow the hatch to be quickly removed. 65

4. The combination, with a tubular support arranged centrally of the roof and having a flange around its lower edge, of radially arranged roof beams having their inner ends secured to said flange, and roof plates 70 fastened upon said beams.

5. The combination, with a tubular support arranged centrally of the roof and having a flange around its lower edge, the upper 75 face of said flange being beveled to conform to the pitch of the roof, of radially arranged roof beams having their inner ends secured to said flange, and roof plates fastened upon said beams.

In testimony whereof, I affix my signature, 80 in presence of two witnesses.

GEORGE W. BOLL.
